UNITED STATES PATENT OFFICE

2,388,921

PORTABLE TRUCK GRAIN ELEVATOR

Ralph L. Kooiker, Hull, Iowa

Application February 10, 1943, Serial No. 475,458

1 Claim. (Cl. 198—115)

My invention relates to a portable grain elevator.

An object of my invention is to provide a portable elevator which can be quickly and readily attached to a truck such as a grain truck or the like and transported to any location, thence quickly detached and used for filling grain bins and the like.

A further object of my invention is to provide a portable grain elevator of this type which can be conveniently elevated to any desired height.

A further object of my invention is to provide means for transporting the elevator with a certain structure included therewith to provide a minimum number of parts so that the elevator will be of a minimum weight and to provide a two-wheeled structure for normal transportation without making the device too bulky, etc.

A further object of my invention is to provide a hopper construction at the lower end of the elevator which can be removed so that the lower end of the elevator can be inserted into the restricted openings in grain bins when it is desired to elevate grain from the bins to a wagon, truck, etc.

A further object of my invention is to provide a driving arrangement which is simple in construction and yet which maintains a constant uniform driving engagement regardless of the position of the elevator.

A further object of my invention is to provide an elevator construction which includes very few parts and to further provide a construction of this type which will not become clogged.

A further object of my invention is to provide a foldable elevator which can be folded when in carrying position so that it will not be of undue length and after being folded can be then extended to normal lengthened position with a certain convenient control therefor.

With these and other objects in view, my invention consists in the construction, arrangement, and combination of the various parts of my device, whereby the objects contemplated are attained, as hereinafter more fully set forth, pointed out in my claim, and illustrated in the accompanying drawings, in which:

Figure 1 is a side elevation of the arrangement,

Figure 2 is a sectional view taken substantially along the lines 2—2 of Fig. 1,

Figure 3 is a sectional view taken substantially along the lines 3—3 of Fig. 1,

Figure 4 is a sectional view taken along the lines 4—4 of Fig. 1,

Figure 5 is a sectional view taken along the lines 5—5 of Fig. 1,

Figure 6 is a detail of the clutch and idler pulley arrangement,

Fig. 7 is a further detail,

Figure 8 is a detail,

Figure 9 is a further detailed view of Figure 8,

Figure 10 is a detail, and

Figure 11 is a detail.

I have used the character 10 to designate the elevator housing which is of substantially U-shape and which includes the bottom 11 and the sides 12, which sides terminate in the flanges 13. The discharge end of the elevator is indicated by the character 14 which is open in the usual manner and which is attached at 15 to the suitable spout 16. When being transported, the spout 16, which can be made of the reversible type, can be turned around and inclined to the position as shown by 20 the dotted structure and hooked at 17 to the elevator housing.

Pivotedly attached beneath the housing is the rod 18 which is attached to the arms 19 which receive the elevator housing therebetween, which 25 terminate at 20. Attached to the arms 19 at 21 are the cables 22 which pass over the pulleys 23 which pulleys 23 are journaled on short shafts 24 which shafts 24 are attached at 25 to the upper ends of the upstanding vertical beams 26, the beams 26 receiving between the chute or 30 housing 10.

Attached to the members 26 at 27 are the brace rods 28 which are attached at 29 to the motor framework or any other portions of the arrangement, and the members 26 are further pivoted at 30 to the ears 31 which ears 31 are attached to the bed plate 32. Mounted on the plate 32 is a suitable motor of any desired type, such as an internal combustion type or the like which is indicated by the character 33 and which is adapted 35 to drive the pulley 34 over which pulley passes the belt 35.

Suitably attached to the plate or base 32 are a pair of springs 36 which are attached to the hubs 37 of the pair of wheels 38, the other extremity of the springs being attached at 39 to a pair of forwardly projecting beams 40 in which beams 40 are journaled at 41 to the shaft 42 (see Fig. 3). Attached to the shaft 42 at one side 45 thereof is the larger pulley 43 over which passes the belt 35. Also journaled on the shaft 42 are the bearings 44 which are attached to the lower deck or bottom 11 of the chute or housing 10.

Attached beneath one of the beams 40 is a bracket 45 in which bracket is pivoted at 46 (see

Fig. 6) the rod 47 which extends through a further bracket 48 which is attached to the other beam 40 at the other side of the arrangement. Extending from the rod 47 is the arm 49 which terminates in the handle 50, and a lock member 51 passes through the arm 49 into the keeper 52 which includes the slot 52a therein so that the member 51 which is engaged through the slot with the threaded nut 51a can be tightened to maintain the arm 49 in any fixed position. The keeper 52 is pivotally secured at 52b (see Figures 8 and 9).

Attached at 53 to the rod 47 is a further arm 54 which terminates in the pulley 55 which pulley 55 is adapted to be pulled against the belt 35 to act as an idler as well as means for starting the arrangement, since the belt 35 is normally maintained in a slackened condition so that when the handle 50 is pulled over toward the left as shown in Fig. 1, the pulley 55 will be brought into engagement with the belt. The member 51 will then permit tightening at any desired position.

The cables 22, after passing over the upper pulleys 23, pass over the windlass 56 which is attached to the shaft 57 which is suitably journaled at 58 to a bracket 59 at one side of the chute, and the other end of the shaft 57 being attached to a suitable worm gear enclosed in the housing 60, which worm gear is driven by a worm attached to the shaft 61 which is turned by means of the handle 62. Attached interiorly of the large pulley 43 is a sprocket 63 over which passes the chain 64 which chain passes over the further idler sprocket 65 and thence over the further sprocket 66 which sprocket 66 drives the elevating arrangement, the elevating arrangement comprising the continuous chain 67 which is attached to the bars or grain paddles 68 and which travels over an upper deck 69 which is spaced above the bottom of the elevator housing.

Attached at 10 to the lower end of the housing (see Fig. 1) is a resilient flap 71 which includes an opening 71a (see Figure 10) for allowing the chain 67 to pass therethrough and which flap is bent and continually displaced by the bars 68 as the grain is being elevated upwardly along the elevator chute and along the deck 69. This provides means for preventing clogging of the lower portions of the elevator inwardly of the sprocket 66 which otherwise would fall through the opening at 72 and have a tendency to jam or clog the arrangement.

The hopper is indicated by the character 13 and includes the inclined side walls 74 and the end walls 75 and 76, the end walls 76 including a suitable opening at 77. Attached to the hopper sides 74 are the lugs 78 which receive the spring bolts 79 which are pivotally attached at 80 to the sides 12 of the elevator chute with the control hand nuts 81 serving as a means to release the spring bolts 79 from engagement with the hopper which is separated as shown at 82 from the balance of the chute, so that in this manner, the hopper can be readily removed from, or attached to, the lower end of the chute.

Straddling the arcuate lower end of the chute is the substantially U-shaped member 83 which is attached to the further U-shaped hitch member 84 which is adapted to normally allow attachment to the projecting hitching portions of the truck (see Figure 11).

It will now be seen from the foregoing description that the device can be transported in the dotted position as shown in Fig. 1 wherein the hitch attachment 85 is attached to the member

84 with the device thus being transported and with the spouts 16 being attached or otherwise. When it is desired to raise grain from the lower position of the truck into the bin, the device will 10 occupy the position as shown in Fig. 1, with the lower end resting on a block such as 86 or on the ground, and the grain is shoveled into the hopper 13 and the engine is started, with the idler or clutch pulley 55 being operated as explained, whereby the grain will be elevated upwardly and thence through the spout 16. The desired elevation is obtained by turning the crank handle 62 which, in turn, rotates the windlass 56, reeling the cables 22 thereon, which allows any selective position of the arrangement.

The detachable hopper 13 provides a desirable arrangement wherein it is possible to convey the grain directly from the grain bin upwardly into a truck or the like, in which case the hopper 13 is removed, as explained, and the arrangement is pushed rearwardly so that the lower end of the chute 10 projects into the grain bin a fairly substantial distance. The grain is then thrown from inside the bin into the lower end of the chute and carried upwardly in the same manner. This is especially desirable in grain bins since only restricted openings are usually provided at the bottoms thereof, which allows reception of the reduced portion of the chute therein.

If it is desired to pass the framework through a smaller opening, as is usual in many cases, the attachment points at 29 of the braces 28 are removed, and due to the pivotal engagement at 30, the beams 26 can be swung to a nearly horizontal position so that the entire portable structure can be moved through lower openings and the like. During transportation of the light arrangement, it is desired to prevent rattling and vibration, and to provide this result I provide the lengthened rod 87 which passes through the opening 88 in one of the members 26 and is threadably engaged at 89 in the other member, and the rod 87 includes the handle portions 90 so that the member 87 can be inserted through the opening 88 and 89 and threadably engaged therewith, thereby locking the chute in fixed and rigid position as shown in Fig. 5 which will prevent the aforesaid shaking, vibration, and the like.

The arrangement such as described is of minimum weight, and I have found that it need not weigh more than approximately eight-hundred pounds including the entire framework, engine, and all, and it provides a balancing effect so that it can even be pushed about by one man if necessary, wherein the lower end can be readily lifted off of the ground after detachment from the conveying vehicle and brought to any desired location.

In transporting the unit, as shown by the dotted figures in Fig. 1, with the end of the unit extending rearwardly, an objectionable feature is sometimes involved wherein the length of the transporting arrangement, is too long as required in some states, and involves a cumbersome structure. To offset this disadvantage I provide a further attachment which will now be described and wherein the chute 10 is made up of the two sections such as 91 and 92. The section 91 includes the flange 93 attached thereto, and the section 92, a further flange 94 which flanges abut against each other. Attached to the flange 4, which flanges, of course, are at either side of the chute portion 92, are the overlapping ears 95, the upper ears of which are attached by means of suitable bolts 96, and passing through the lower ears.

95 is a rod 96a which passes beneath the chute and through the other ears 95 at the other side thereof.

It will be understood that the ears 95 engage suitable ears on the flanges 93. Also attached at each side of the chute 10 are the members 97 which are attached at 98 to the sides of the chute (see Fig. 7), which members include the cylindrical portion 99 and the expanded cylindrical portion 100, the portion 100 being adapted to be disposed laterally beyond the cable 22. Attached at 101 to the member 40 are a pair of bracket members 102 which terminate in a cradle member 103 which cradle member is substantially U-shaped to receive the end of the chute 92.

In transporting the structure and before transportation thereof, the lower rod at 96a is removed, leaving the upper bolts 95 in position. The member 87 is then locked in position and the windlass 56 is then operated which pivots the upper portion 92 about the portion 91, since the portion 91 will be held in horizontal position.

The cables 22 are wound until the members 97 receive the same between the sides of the chute and the portion 100 and the chute end 92 will fall to the position as shown by the dotted structure in Fig. 1, and until it is received by the cradle 103, where it will be retained in inoperative and transporting position. In this manner the device can be transported to any location without the extra length extending behind the trailer structure.

When it is again desired to use the chute arrangement, the forward end of the unit is lowered as shown in Fig. 1 and the windlass is operated drawing the cables 22 which, due to the engagement of the cables 22 about the members 97, will raise the portion 92 towards a vertical position, and then when the forward end of the arrangement substantially at 84 is raised slightly, the 40

member 92 will fall over past center and then can be released slowly until the members 91 and 92 are in alignment. The bar 96a is again replaced, thereby resulting in the completed chute structure ready for use which can then be manipulated again for the purpose intended.

It will now be seen that my invention provides all of the advantages enumerated heretofore and includes many other advantages readily apparent.

Some changes may be made in the construction and arrangement of the parts of my invention without departing from the real spirit and purpose of my invention, and it is my intention to cover by my claim any modified forms of structure or use of mechanical equivalents which may be reasonably included within their scope.

I claim as my invention:

A portable elevator comprising an elevator chute, a framework supporting said chute including a pair of vertical beams receiving the chute therebetween, said chute being pivotally attached to said framework, a windlass attached to said chute, pulleys attached between said vertical beams, cables attached to said chute passing over said pulleys and to said windlass to provide means for elevating said chute to desired elevation, said chute including a forward section, a rearward section pivoted to said forward section, means for folding said rearward section over said forward section to provide a reduced length to the elevator when being transported, means for extending said rearward section to completed length including side members attached to said rearward section adapted to engage said cables, 35 whereby raisable movement of said cables will pivot said rearward section on said forward section to said completed length, a cradle member attached to said framework for supporting said rearward section when in folded position.

RALPH L. KOOIKER.
